UNITED STATES PATENT OFFICE

LESTER T. LLOYD, OF OAK PARK, AND HENRY E. OLSEN, OF CHICAGO, ILLINOIS,
ASSIGNORS TO W. G. LLOYD COMPANY, OF CHICAGO, ILLINOIS, A CORPORATION OF
ILLINOIS

BINDER

Application filed May 2, 1930. Serial No. 449,292.

This invention relates to binders and particularly binders in which an adjustable clamping member is secured to a binder post.

The primary object of the invention is to 5 provide an improved device for detachably locking the adjustable clamping member or members to the posts.

The invention, in its preferred embodiment, is illustrated in the accompanying 10 drawings, in which—

Figure 1 is a perspective view of the clamping member and post mechanism embodying our invention;

Fig. 2 is a broken sectional view, the section being taken as indicated at line 2 of Fig. 15 1, and showing the locking member engaging the post;

Fig. 3 is a broken sectional view, the section being taken as indicated at line 3 of 20 Fig. 1, and showing the opposite end of the adjustable clamping member;

Fig. 4 is a broken sectional view, similar to Fig. 2, showing the locking member released from engagement with the post;

Fig. 5 is a plan view of the slide which is 25 shown in Figs. 2 and 4;

Fig. 6 is a view in elevation of the slide;

Fig. 7 is a plan view of one form of locking member or dog;

Fig. 8 is a part sectional view, the section being taken as indicated at line 8 of Fig. 7;

Fig. 9 is a plan view of the special form of spring employed;

Fig. 10 is a sectional view, the section being 35 taken as indicated at line 10 of Fig. 4, the post having been removed;

Fig. 11 is a plan view of another form of a locking member or dog; and

Fig. 12 is a side view of the locking member shown in Fig. 11.

Referring to the drawings, A represents a lower clamping member from which rise posts B; and C, an upper clamping member which is adjustably mounted on posts B.

45 The clamping members A and C may be secured to cover sections in any desirable manner. If desired, they may be secured to cover sections in the manner illustrated and described in Olsen Patent No. 1,370,149.

50 The lower clamping member A may be of

any suitable or approved construction. As shown in this instance, it comprises a sheet member bent into hollow form and provided at its ends with blocks 1 which serve to close and protect the ends. Blocks 1 may be secured within the clamping member A by rivets or any other suitable means. The member A is perforated at 2 to receive a reduced end 3 of the binding post B. The lower wall of the member A may be perforated at 4 to provide a smaller opening through which a smaller reduced end 5 of the post extends. Post B may be secured in position by screws or rivets 6. Clamped between the two walls of member A and secured therein is a ring 7 which encircles and supports the reduced end 3 of the binding post.

The upper clamping member C is made hollow to contain the improved devices for releasably locking it to the posts B, and it preferably consists of a sheet metal member which is formed similarly to that of the lower clamping member A, and which has in its end portions plugs 1 similar to those in member A. The blocks or plugs 1 may be secured in position by rivets or other suitable means. The member C is perforated to receive the posts B. Also, the upper wall of the member C is slotted to provide an oblong opening 8.

The improved devices for releasably locking the clamping member C to the posts B are constructed as follows:

Slidably supported near the top of member C is a slide bar 9 which is equipped centrally with a handle or knob 10 adapted to extend through slot 8. The slide bar 9 is preferably provided with a pair of downwardly struck flanges 11, which are preferably formed from opposite sides and opposite ends of the bar, as shown more clearly in Figs 5 and 6. With this construction, the flanges 11 support the slide evenly against the top wall of the clamping member C and permit it to be reciprocated with very little friction. The bar is carried between the posts B and is provided at each of its ends with a kink or inclined surface 12.

Engaging each of the posts is a rocking member 13. This member comprises a wide

flat surface 14 and rocker portion 15 and a cam portion 16. The flange portion 14 is provided with a relatively large opening 17 adapted to receive a post B, a pair of rivet 5 openings 18 and a pair of spring end openings 19. In the form illustrated in Figs. 7 and 8, the rocker portion 15 comprises a pair of legs 20 and a centrally disposed neck 21 which is integrally formed with the cam portion 16. The cam 16 preferably comprises a long inclined surface provided with a rounded end portion 22. The locking members or dogs are preferably of the same construction and may be used interchangeably 10 at either end of the clamping member. To secure each of the locking members 13 to the clamping member C, a pair of rivets 29 are passed through the openings 18 in the dog or locking member and are secured to the upper 15 and lower walls of member C. Sufficient play is provided between the rivets 29 and edges of the openings 18 to permit the locking member to rock to the lowered and raised positions illustrated in Figs. 2 and 4.

25 A spring 24 is employed to urge the dog or locking member 13 toward its lowered position in which it engages the post B. The spring is preferably of the U-shaped form shown in Fig. 9 and is provided at its ends 30 with coils 25. The extreme ends 26 of the spring are preferably extended so as to pass through the openings 19 in the locking member 13. The ends 26 are preferably pressed down against the top of the flange 14 to secure the spring to member 13, as illustrated more clearly in Figs. 2, 3 and 4. In the position illustrated in Figs. 2, and 3 and 4, the rear side of the spring 24 lies against the top wall of clamping member C and the spring 35 coil is so tensioned as to cause the extension 40 to exert a downward pressure against the flange 14 of the locking member 13.

In the form of locking member illustrated in Figs. 11 and 12, the rocking portion 27 is 45 not cut away to form legs 20 of the form shown in Fig. 8, but the entire lower portion is curved so as to form a half-cylindrical rocker bearing. This form of construction provides a sturdier connection between the 50 cam and the flange portions of the locking member and also provides a rocker bearing which operates with little friction.

The rounded surface 22 upon the cam 16 is preferably long enough to permit the end 55 12 to rest thereon securely when the member 13 is rocked into its raised position to release the post B. By this means, when the rocking member is raised, the member will remain in its raised position without exerting 60 further pressure upon the slide bar 9.

In the operation of the apparatus, the movement of the slide bar by means of the handle or knob 10 brings the ends 12 into engagement with the cam 16. In the normal 65 locked position, the spring 24 maintains the

flange 14 of the locking member at the inclined angle illustrated at Figs. 2 and 3. Continued longitudinal movement of the slide bar 9 brings the ends 12 into contact with the cams of the locking member and depresses the cams, thus rocking the member so as to raise the flange portion out of binding engagement with the post B. As shown more clearly in Figs. 2 and 3, the end 12 at one end of the slide engages the outer end 70 of cam 16, while the end 12 on the opposite end of slide 9 engages the inclined surface of the inner side of cam 16, so that at one end the end 12 is pushed against the cam surface while at the other end it is pulled 75 against the cam surface. In both operations the cam is depressed and the flange 14 is raised, rocking upon the rocker point 15 as a pivot. When the flange portion 14 of the locking member has been raised to release the post B, as shown more clearly in Fig. 4, the end 12 rests upon the top point 80 22 of the cam and serves to retain the locking member against the force of spring 24 85 in raised position.

With the flange 14 of the locking member in raised position, the clamping member C may be freely raised or lowered upon the posts B. When it is desired to again lock 90 the clamping member C upon the posts B, the slide bar, by means of knob 10, may be moved in the opposite direction so as to release the ends 12 from engagement with the cam surfaces. The force of spring 24 will then depress flange 14 of the locking member 95 so as to bring the edge of the opening 17 into binding engagement with the post B. Any tension brought to bear to separate the members A and C will tend to further clamp the flange 14 of locking member 13 against the 100 binding post B.

With the construction illustrated, it will be observed that the rocking members are 105 operated by a slide supported adjacent the top wall of the clamping member C and between the two binding posts B, thus affording a compact and sturdy locking mechanism. The rocking members which serve to lock the clamping member C to the posts 110 are so constructed as to have a relatively long stroke. This enables a stronger grip action when the clamping member is locked to the post and further enables the adjustable clamping member to be completely released 115 from the post without danger of binding.

It will be evident that the improved locking device is simple and effective, and that the clamping member C cannot be accidentally released from the posts B, when it is in locked position, as when the binder is thrown 120 upon a table.

While in the illustration given, a slide bar 125 is shown as the means for rocking the locking members, it is obvious that other means, such as for example, push buttons, may be 130

employed to rock the members into locked and into unlocked position.

No unnecessary limitation should be understood from the foregoing detailed description which has been given for clearness of understanding only; but the appended claims should be construed as broadly as is permissible in view of the prior art.

I claim:

- 10 1. A binder comprising, a post, a hollow clamping member movably fitted thereon, a rocking member having openings therein and equipped with a perforated flange adapted to receive said post, said rocking member being provided with a rocker edge portion and a lever arm extending upwardly from said rocker edge portion, pins extending through said openings in said rocking member to prevent longitudinal displacement, and means 15 adapted to engage said lever arm to tilt said rocking member.
- 20 2. In a binder equipped with a post and a hollow clamping member movably fitted thereon, a rocking member provided with a 25 perforated flange adapted to receive said post and also equipped with a rocker edge portion adapted to rest upon the bottom wall of said clamping member, said rocking member being provided with a lever arm connected to said rocker edge portion, means 30 associated with said rocking member and said clamping member to prevent longitudinal displacement of said rocking member, spring means adapted to urge said perforated flange in a downward direction, and means for exerting pressure upon the lever arm in order to tilt said rocking member.
- 35 3. A binder comprising, a post, a hollow clamping member movably fitted thereon, a 40 rocking member equipped with a perforated flange receiving said post, said rocking member having a rocker edge portion and a lever arm extending upwardly from said rocker edge portion, means associated with said 45 rocking member and said clamping member to prevent longitudinal displacement of said rocking member, spring means adapted to urge said perforated flange in a downward direction, and means adapted to engage said 50 lever arm to tilt said rocking member.
